UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed July 30, 1924. Serial No. 729,007.

This invention relates to the cylindrical platens of typewriting machines, which ordinarily have body-portions of hard rubber, so that sufficient rigidity is provided for 5 typing thereon, but which are noisy.

It is the primary object of the present invention to provide a platen that will at once be rigid enough for typing thereon and yet be so constructed as to minimize the noise 10 from the blows of the type-bars. This is done by making the platen coreless, and forming it largely of sufficiently soft rubber. Means is provided to overcome the 15 objection to a substantially coreless platen made of soft rubber, that upon being struck by the type-bars it would be apt to yield with or bend bodily, the result that no impression or a blurred one would be made on the work-sheet, and to overcome the objection 20 due to the flexibility of the soft coreless platen, the constant use of which would tend to warp or distort it and render it inefficient. These objections are taken care of in the present invention by providing the 25 platen with a support which bears at a point against the platen opposite where the blows are struck by the type-bars, said support preferably in the form of a metal shield or shoe, the curvature of which conforms to 30 the curvature of the platen and extends preferably the whole length thereof. The shield may encompass the platen for about one-third of its circumference. Said shield 35 may be rigidly suspended from the paper-engaging finger-guide-rod of the machine, and, although engaging the exterior of the platen, will permit the platen to rotate freely. This shield supplies the platen with the necessary rigidity to withstand the blows 40 from the type-bars and protects it from becoming bodily distorted. The coreless body of the suitably soft rubber platen reduces the noise from the type-bars to a minimum.

Other features and advantages will hereinafter appear.

In the accompanying drawings,

Figure 1 is a top plan view of a typewriter with the present invention applied thereto.

Figure 2 is a side view looking to the left of Figure 1, showing how the shield is mounted and engages the platen.

Figure 3 is a vertical sectional view, showing a platen embodying the present improvements.

Referring to Figure 1, a platen 1 is mounted on a shaft 2 journaled in platen-frames 3 and 4. Ordinarily, the platen 1 comprises a core of some hard substance and a covering of hard rubber. By reason of such a 60 construction, the pounding of the type-bars on the platen makes considerable noise, which is objectionable.

In accordance with the present invention, the platen 1 consists of a tubular body-portion 5 made of semi-soft rubber and an outer covering 6 of somewhat harder rubber. Said body-portion 5 and covering 6 are secured by means of nails 8 to soft rubber end pieces 7 at the ends of the platen. Said end pieces 70 7 are bored at 9. Into the bores 9 of the end pieces 7 are inserted the hubs 10 of bored metal side plates 11. Said side plates 11 are securely mounted by means of screws 12. Through the bores of the end pieces 7 and 75 side plates 11 passes the shaft 2, which is insulated by the rubber end pieces 7 and is held in place by set-screws 13. The end pieces 7 may be made of wood in some cases. Mounted on the end of the shaft 2 is a hand-wheel 14 for rotating the platen. Extending between the platen-frames 3 and 4 and to the rear and above the platen 1 is a rod 15. This rod 15 usually has hinged and slidably mounted thereon curved paper-engaging 80 fingers 16, supporting rolls 17 and 18 which press a work-sheet 19 against the platen 1.

Such a flexible platen, when struck a blow by the type-bars in typing, tends to flex or 90 give, resulting in a blurred or poor impression, and there is also a tendency towards distortion of the platen. According to the present invention, these objections are overcome by providing the platen with a reinforcing shield 23 to render it sufficiently 95 rigid to withstand the blows of the type-bars and to protect it from becoming distorted. This shield 23 encircles the platen directly opposite the printing point and the feed-rolls. Said shield comprises a curved metal 100 body-portion 24 extending the length of the platen 1. The curvature of this body-portion 24 conforms to the curvature of the platen 1 and encircles it for about one-third 105 its circumference. It is rigidly suspended from the rod 15 by means of bored ears 25, and it frictionally engages the platen 1.

It will be noted from Figure 2 that the shield encircles the platen 1 for about one- 110

third its circumference, extending along the rear and top sides of the platen from a point on the circumference of the platen below the printing point thereon, indicated by the 5 type 20, to a point on the circumference of the platen above the printing point thereon, directly opposite the feed-rolls 21. By positioning the shield on the platen at the points indicated, the shield acts as a reinforcing 10 agent, imparting sufficient rigidity to the coreless platen to permit satisfactory typing thereon and to prevent it from becoming distorted.

Variations may be resorted to within the 15 scope of the invention, and portions of the improvements may be used without others.

Having thus described my invention, I claim:

1. A noiseless typewriter platen, including 20 a coreless body portion of sufficiently soft rubber for typing, and non-revoluble means exterior of said body portion and movable laterally therewith, which permits typing on said body portion, and renders a sufficiently 25 rigid support to prevent bodily bending of the platen by said typing.

2. A noiseless typewriter platen, including 30 a tubular rubber body portion, a rubber covering for said body portion, the latter being softer than said covering, and non-revoluble exterior platen-supporting means movable laterally with said covering and arranged at the rear thereof and supporting said platen with sufficient rigidity for typing 35 on said platen and to prevent bodily bending thereof.

3. A noiseless typewriter platen, consisting 40 of a tubular body portion made of semi-soft rubber, a covering for said body portion made of rubber harder than said body portion, and a non-revoluble metal shield in contact throughout with said covering and extending the length of said covering and encompassing it at the rear for substantially 45 one-third its circumference, and supporting the platen against bodily bending at the type-blows.

4. A noiseless typewriter platen, including 50 a tubular body portion made of semi-soft rubber, a covering for said body portion made of rubber harder than said body portion, and a concave, non-revoluble metal shield extending the length of said covering and encompassing it for substantially one-third its circumference, said shield engaging the covering lightly at the rear throughout 55 its length to permit the platen to rotate.

5. In a typewriting machine, in combination, 60 a noiseless platen for holding a work-sheet, said platen including a coreless rubber body portion and a harder rubber covering therefor, a carriage-rod, feed-rolls mounted

on said rod and arranged for pressing said work-sheet against the platen, type for printing on said work-sheet, and means mounted 65 on said rod positioned with respect to said rolls and type and in engagement with the platen to afford the necessary rigidity to said platen to permit typing thereon and to prevent bodily bending thereof from pressure 70 exerted by the blows of the type and by the feed-rolls, said means being mounted to permit free lateral adjustment of said feed-rolls.

6. In a typewriting machine, in combination, 75 a noiseless platen for holding a work-sheet, said platen consisting of a coreless rubber body portion and a sufficiently soft rubber covering therefor, feed-rolls for pressing said work-sheet against the platen, a rod mounted parallel with said platen, type for 80 printing on said work-sheet, and a metal shield suspended rigidly from said rod and engaging said platen frictionally, said shield comprising a curved body portion extending the length of the platen and encircling the 85 rear and top of said platen from a point on the circumference of the platen below the printing point thereon to a point on its circumference opposite the feed-rolls, and supporting the platen against bending bodily 90 under the type-blows.

7. A noiseless typewriter platen, including 95 a coreless body portion of soft rubber suitable for typing, non-revoluble means exterior of said body portion arranged to move laterally with the same at the rear thereof to make it sufficiently rigid for typing thereon and to prevent bodily bending thereof, and soft rubber end pieces supporting said body portion.

8. A noiseless typewriter platen, including 100 a tubular rubber body portion, a rubber covering for said body portion, the latter being softer than said covering, non-revoluble and laterally-movable means arranged at the rear 105 of said body portion away from the printing line, to make said platen sufficiently rigid for typing thereon and to prevent bodily bending thereof, and soft rubber end pieces supporting said body portion.

9. A noiseless typewriter platen, consisting 110 of a tubular body portion made of semi-soft rubber, a covering for said body portion made of rubber harder than said body portion, a non-revoluble metal shield in contact 115 throughout its length with said covering and extending the length of said covering and encompassing it for substantially one-third its circumference and arranged to permit typing on said covering, and soft rubber end pieces supporting said body portion, said shield supporting said body portion against bending under the type-blows.

ALFRED G. F. KUROWSKI.
